UNITED STATES PATENT OFFICE.

QUINCY A. SHAW, OF BOSTON, MASSACHUSETTS.

GREEN SWEEPER.

Application filed February 15, 1927. Serial No. 168,378.

The present invention relates to a ground-treating device, more particularly a sweeper for reconditioning the grassy surface of golf greens or the like. Heretofore it has been common to sweep golf greens by the use of brushbrooms of various types and bamboo poles; this requiring considerable labor in order to cover a reasonable ground area. Whenever use of comparatively wide brushes was attempted for this purpose, the result was generally unsatisfactory since irregularities, which occur in the surface of the ground, resulted in too harsh treatment of the protuberant portions of the ground and the passing over of the hollows or reentrant portions thereof. Thus grass upon the miniature hillocks tended to be worn away by frequent bearing of the brush thereon while grass in the intermediate hollows would remain untouched by the wide brush. Irregular treatment of the surface in this manner would result in a green wherein the uncertainties of putting were augmented and in which the appearance of the greensward was unsatisfactory.

The present invention is intended to obviate these difficulties by providing a series or gang of ground-treating elements, preferably brushes, which are secured to common means for drawing them over the ground by articulated connecting elements arranged in a manner which somewhat resembles the combination of doubletrees and singletrees which is well known in horse-drawn vehicles. These individual brushes or sweeping elements are swiveled or pivoted in relation to each other to conform to small irregularities in the ground surface, while means are arranged for the pivoting of a plurality of sweepers in relation to each other to compensate for larger irregularities, these two means, which permit pivoting in the manner indicated, being adapted to permit multifarious relative movements between the sweeping elements in order to permit them to follow the contour of the ground no matter what the irregularities thereof may be.

The above and further objects of the invention will be apparent to those skilled in the art upon a reading of the subjoined description and claims in conjunction with the accompanying drawings, in which:

Fig. 1 is a side view of the device in its operative position;
55 Fig. 2 is a front elevation of the same;

Fig. 3 is a plan view of the device; and Fig. 4 is a section on line 4—4 of Fig. 3.

A green sweeper of the type disclosed in the accompanying drawings may conveniently comprise a main cross bar 1 which, as shown, is rigidly connected to a stub tongue 2 in order to provide a framework of substantially T-shaped configuration. At either end of the cross bar 1 are pivoted the intermediate portions of the support bars 3, to the ends of which in turn are pivoted the intermediate portions of the individual brush or sweeping elements 4. Any suitable flexible means such as the chains 5, Fig. 2, are adapted loosely to tie the ends of the brush elements to each other in order to limit the relative movement between the same. The preferred manner of securing and pivoting the support bars to the cross bar and the sweeping elements to the support bar is shown in Fig. 4, from which it is apparent that a suitable bolt 7 may be fixed in one element as in the bar 3 and may pass through the bushing 9 which has been pressed into the element pivoted thereto, such as the sweeping element 4.

Preferably the bushing 9 extends outwardly beyond the surface of the member 4 adjoining member 3 in order to engage a washer 10 and to comprise a spacer to hold the elements at a suitable distance apart in order to provide proper clearance for the same. Suitable washers 12 may be located under the nuts 13. It is thus evident that a simple and inexpensive means is provided for pivoting the various elements of the sweeping device to each other, the bushing 9 in each case not only serving to prevent wear of the swivel or pivot member but also serving as a spacer for the same.

Obviously the components of the invention may be considerably varied and, while I have shown the brushes 4 as the preferred form of ground-treating elements, it is obvious that the design of these members may be varied to suit different conditions. It is also to be understood that the number of support bars or the number of individual sweeping elements upon each support bar may be varied as desired without departing from the spirit of this invention, as long as a plurality of independently pivoted ground-treating elements are supported from a common framework or cross bar to which the draft means or tongue is secured.

Obviously this device is intended to be used in the manner common with the green sweepers previously known in the art, being drawn by a rope or any suitable flexible element which is attached to the end of stub tongue 2 in order to draw the brush elements over the ground.

I claim:

1. A device of the class described comprising a series of green sweeping elements, means for moving the elements along the ground, a cross piece connected to said means, and a plurality of members pivotally connected to said cross piece, each of said members carrying a plurality of the green sweeping elements pivotally mounted thereon.

2. A device of the class described comprising a plurality of green sweeping elements, a main cross bar, draft means connected to the cross bar, a plurality of support bars pivoted to the cross bar, a plurality of green sweeping elements pivoted to each support bar, and flexible means between the

green sweeping elements limiting the relative movement of said elements. 25

3. A device of the class described comprising a plurality of substantially aligned green sweeping elements, a main cross bar, draft means connected to the cross bar, a 30 plurality of support bars pivoted to the cross bar, a plurality of green sweeping elements pivoted to each support bar, and flexible means limiting the relative movement of said elements, said draft means comprising a short tongue projecting from the main cross bar at an angle to the plane of the green sweeping elements. 35

4. A device of the class described, comprising a plurality of green sweeping elements, a main cross bar, draft means connected to the cross bar, and support bars pivoted to end portions of the main cross bar a green sweeping element being pivoted to each end of each support bar. 40 45

Signed by me at Boston, Massachusetts, this 14th day of February 1927.
